UNITED STATES PATENT OFFICE.

RICHARD H. GOLDSBOROUGH, OF WASHINGTON, DISTRICT OF COLUMBIA.

TURBINE.

No. 869,896.

Specification of Letters Patent.

Patented Nov. 5, 1907.

Application filed March 11, 1907. Serial No. 361,738.

To all whom it may concern:

Be it known that I, RICHARD H. GOLDSBOROUGH, a citizen of the United States, residing at Washington, District of Columbia, have invented certain new and 5 useful Improvements in Turbines, of which the following is a specification.

My invention relates to improvements in turbines and it consists in the constructions, combinations and arrangements herein described and claimed.

10 An object of my invention is to provide a compact form of compound turbine adapted to efficiently utilize a high degree of expansion in the actuating medium.

A further object of my invention is to provide a compound turbine, in which heat can be imparted in an 15 efficient manner to the actuating medium during its flow through the successive stages, for augmenting the power of the turbine to accommodate great and sudden increases in its load.

20 A further object of my invention is to provide a compound type of turbine, constructed to operate with a substantially constant efficiency through large variations in the relation of the rotor speed to the velocity of the actuating medium.

25 A further object of my invention is to provide a compound type of turbines which can be started under load from a position of rest, without the necessity of extraneous turning of the rotor, and which will operate efficiently at constant rotor speed under throttle control of the actuating medium.

30 A further object of my invention is to provide an improved form of compound turbine, in which clearance leakage will be minimized, and any tendency to such leakage will be automatically checked.

In the accompanying drawings, forming a part of this 35 application, and in which similar reference symbols indicate corresponding parts in the several views: Figure 1 is a vertical axial sectional view, on the line 1—1, of Fig. 2, illustrating one embodiment of my invention; Fig. 2 is a sectional view on the line 2—2, of Fig. 1, 40 clearly showing the arrangement of the admission ports and the superheating means; Fig. 3 is a sectional view on the line 3—3, of Fig. 1, showing the arrangement of the exhaust ports. Fig. 4 is a perspective view of a portion of the port ring, with the two sections of said ring 45 properly assembled; Fig. 5 is a perspective view of one section of the port ring, clearly showing the exhaust ports therein; Fig. 6 is a detail sectional view on the line 6—6, of Fig. 2; Fig. 7 is a development of the outer periphery of the port ring; and Fig. 8 is a similar development of the inner periphery of the port ring.

50 Referring to the drawings, 1 indicates a turbine shaft suitably journaled in the casing heads 2, which latter are secured by bolts 3 to internal annular flanges 4 on a cylindrical member 5 of the turbine casing. A central

partition 6 is secured to the member 5 by bolts 7, to provide two independent steam chests 8 between said partition and the annular flanges 4 of said member; said partition preferably extending around the member 5 to the point of final exhaust from the turbine casing, as shown especially in Fig. 3. A cylindrical division plate 9, 60 closely fitting the inner peripheries of the annular flanges 4 and partition 6, is provided with apertures 10 for establishing communication between the steam chests 8 and the initial admission ports of the turbine, an opening 11 being provided in said cylindrical division plate for permitting escape of the final exhaust from the turbine casing. Two similar port ring sections 12 are provided on their adjacent faces with series of co-operating recesses, constituting exhaust ports, and on their outer sides with series of recesses constituting admission ports. A series of recesses 15 to 21, extending across the outer peripheries of the port ring sections, 70 constitute chambers which connect the outer ends of the exhaust ports and admission ports together in groups.

75 The admission ports are arranged in series of successive groups 23 to 30, and the exhaust ports are arranged in a corresponding series of successive groups 31 to 38. The ports of said successive groups are shown having a uniform axial dimension, and a progressively 80 increased peripheral dimension for accommodating the expansion of the actuating medium during its flow therethrough. Since the exhaust ports are common to the two lateral series of admission ports, they are given a sufficient axial dimension to accommodate the exact 85 form of both of said admission sets. The inner ends of both the series of admission ports and exhaust ports are arranged to extend continuously about a portion of the periphery of the rotor; the exhaust port series extending from the rear wall of the admission port 23 to a 90 point 39 at a considerable angular advance to the forward wall of the final admission port 30. This relative position of the continuous series of admission and exhaust ports, together with the connection and grouping of the ports, provides an improved construction, capable 95 of operating with a substantially constant efficiency through large variations in the relation of the rotor speed to the velocity of the actuating medium, and in which the rotor can be started under load from a position of rest. This provides a very satisfactory 100 construction, which will operate at high efficiency under throttle-control of the actuating medium, thereby eliminating the defects and mechanical difficulties encountered in the use of internal valves.

105 A closure ring 22 is positioned at the admission-port side of each port ring section, for closing the open sides of the recesses constituting the admission ports. The port ring sections and closure rings closely engage the

inner periphery of the cylindrical division plate 9, and are securely clamped together by the heads 2 of the turbine casing; suitable packing means, such as copper gaskets, may be employed for insuring a steam joint 5 between the several parts.

As shown especially in Fig. 2, each steam chest 8 is divided into a series of communicating chambers by a series of partitions 40, 41, 42, 43, 44, 45, 46 and 47; said partitions being provided with apertures 48. A valve 10 49, controlling the aperture in the first partition 40, is shown threaded in the casing and provided with a hand wheel 50 for actuating said valve to open and close the aperture for admitting or cutting off the supply of steam from the initial steam chambers through the 15 communicating series of chambers.

The communicating chambers are preferably formed of progressively increased volume and arranged to subtend the several groups of admission ports. This provides a simple and very efficient means for superheating 20 the actuating steam of the turbine during its flow through the successive groups of admission ports; the pressure and temperature of the superheating steam being gradually reduced during its flow through the successive chambers of the communicating series, thus insuring 25 an approximately uniform relation between the temperatures of the superheating steam and motor-actuating steam at all of the several stages of the turbine.

The rotor vanes are shown of substantially W-shaped form, to provide two inlet legs 51 and a common central 30 exhaust leg 52, which latter is connected to the inlet legs by curved portions 53 of somewhat greater width than that of said legs.

The annular series of turbine vanes is clamped between inner annular members 54, 55 and 56 seated on 35 the periphery of a drum member 59, and outer annular members 57 and 58; the member 55 being formed in segments for convenience in assembling the parts. The inner annular members are securely clamped together between the rotor disks 60 by means of a series of bolts 40 61^a, which constitute a common means for securely locking together said annular members, drum and rotor disks.

Packing members 61 are secured to any suitable part of the stator, as to the rings 22, and provided with faces 45 62 extending across the clearance about the periphery of the rotor, said packing members extending inwardly to provide annular chambers 63, and carrying at their inner ends suitable packings 64. The packing members can be conveniently constructed of annular plates, 50 or of closely fitting segmental plates. This provides a simple and compact construction by which any steam leaking through the peripheral clearance of the rotor will be entrapped in the annular chambers 63, and thereby engender a pressure in said chambers tending 55 to oppose further leakage.

In the operation of my invention, the steam, or other actuating medium, is conducted by the main supply pipes 65 to the initial steam chests, from which it is directed by the initial admission ports 23 at an effi- 60 cient angle against the legs 51 of the rotor vanes. The steam thus directed through the legs 51 is deflected by the curved portions 53 of the vanes, which latter are shaped to direct the steam in an efficient direction against the common exhaust legs 52 of the vanes. The 65 increased width and shape of the curved vane portions

53 produces a slight regeneration of pressure in the steam flowing therethrough thereby increasing the effective action of the steam on the admission and exhaust legs and minimizing the friction of the steam during its deflection. The steam is discharged from the 70 outer edges of the exhaust legs 52 into the recess 15, which extends across the outer peripheries of the port rings and conducts the steam laterally in both directions to the next two sets of admission ports 24. The steam is directed by the admission ports 24 through the 75 admission legs 51 of the vanes; from which it is discharged from the outer edges of the exhaust legs 52 of the vanes into the second peripheral recess 16 in the port rings. The recess 16 is formed to divide the steam and conduct it to the next two sets of admission 80 ports 25; and the above steps are repeated until the steam is discharged through the final set 38 of exhaust ports, from which it is conducted by a conduit 66 to the atmosphere, or to a condenser.

As shown especially in Figs. 1 and 3, a deflector 67 is secured to the cylindrical division plate 9 in position to extend within each of the recesses in the peripheries of the port rings for splitting the stream of steam discharged therein and deflecting such steam with a minimum of frictional and eddy-current losses. 85

I have illustrated and described a preferred and satisfactory construction, but, obviously, changes could be made within the spirit and scope of my invention.

Having thus described my invention, what I claim as new therein and desire to secure by Letters Patent 95 is:

1. In a compound turbine, the combination of a rotor, an annular series of rotor vanes provided with admission and exhaust edges extending to the periphery of said rotor, a continuous zone of admission ports extending along said 100 admission edges, and a continuous zone of exhaust ports extending along said exhaust edges throughout the angle subtended by said zone of admission ports and extending beyond the final admission ports of said zone, substantially as described.

2. In compound turbine, the combination of a rotor, an annular series of rotor vanes provided with admission and exhaust edges extending to the periphery of said rotor, a continuous zone of admission ports extending along said admission edges, and a continuous zone of exhaust ports 110 extending along said exhaust edges, said zone of exhaust ports extending from the angular position of the initial admission port to a point beyond the final port of said zone of admission ports, substantially as described.

3. In a compound turbine, the combination of a rotor, an annular series of rotor vanes provided with two lateral admission portions and a common central exhaust portion, means for initially directing an actuating medium through said two admission portions of the vanes, and means for repeatedly directing the discharge of such medium from the central exhaust portion again to the two lateral admission portions of the vanes, substantially as described. 115

4. In a compound turbine, the combination of a rotor, an annular series of rotor vanes provided with two lateral admission portions, and a common central exhaust portion, means for initially directing an actuating medium through said two admission portions of the vanes, and means for dividing the discharge of such medium from the exhaust portion of the vanes and directing it again to the two lateral admission portions thereof, substantially as described. 120

5. In a compound turbine, the combination of a rotor, an annular series of rotor vanes provided with two lateral admission portions and a common central exhaust portion, means for initially directing an actuating medium through said two admission portions of the vanes, means for repeatedly directing the discharge of such medium from the central exhaust portion again to the two lateral admission 125 portions of the vanes, substantially as described. 130

portions of the vanes, and means for heating such discharge prior to its several admissions to the vanes, substantially as described.

6. In a compound turbine, the combination of a rotor, an annular series of rotor vanes provided with two lateral admission portions and a common central exhaust portion, series of admission ports and exhaust ports extending, respectively, along said admission and exhaust portions of the vanes, means for supplying an actuating medium to the initial ports of such admission series, and means for conducting the discharge from the exhaust portions of the vanes to the next succeeding ports of said admission series, substantially as described.

7. In a compound turbine, the combination of a stator, a rotor supported in said stator to provide a suitable clearance space between said parts, packing members carried by said stator and extending across the ends of said clearance space, and packings carried by said members in engage-

ment with said rotor at a distance from said clearance space, substantially as described.

8. In a compound turbine, the combination of a stator, a rotor supported in said stator to provide a suitable clearance space between said parts, packing members carried by said stator, and extending past said clearance space and along a portion of said rotor at a distance from the latter, and packing means carried by said members in engagement with said stator for providing between said rotor and members inclosed chambers in communication with said clearance space, substantially as described.

In testimony whereof I affix my signature in presence of 30 two witnesses.

RICHARD H. GOLDSBOROUGH.
